GOLF PRACTICE BALL

Luther I. Clark, Hewlett, N. Y.

Application July 27, 1932, Serial No. 624,951

7 Claims. (Cl. 273—35)

My present invention relates to an improvement in golf practice devices and has for its principal feature, the use of a similitude of a golf ball of great flexibility, which may be anchored in a suitable manner, for practice striking with a golf club, upon the ground or other suitable foundation.

The important feature of the present invention is in the structure of the hollow practice ball, which is, in part, made in the similitude, and approximately the size of a standard golf ball, is made of soft rubber, with relatively thin walls but which has a solid depending, resilient, integral neck piece.

Further, the ball structure, which is hollow, is provided with a breather aperture of relatively large proportions, so that upon striking the same with a club, the flexible or elastic ball collapses under impact of the club, although, as it simultaneously flexes, it travels with the club in the direction of the stroke, for a short movement thereof. Thus the action is somewhat phantom-like, in play.

A further feature of the present device is in the provision of the flexible or resilient neck piece, noted above. While the ball portion of the device is made of thin rubber, in the form of a hollow sphere, it has a depending neck portion of solid rubber. The neck portion is moulded integrally with the ball portion. The neck portion may be so shaped in contour as to permit it to be anchored to the ground, for play, or may be otherwise mounted for play practice. The foregoing and other capabilities will be apprehended as the herein description proceeds and it is obvious that modifications may be made in the herein described device, without departing from the spirit hereof, or the scope of the appended claims.

In the drawing, Fig. 1 is a plan view of my device, as shown in Fig. 2; Fig. 2 is a sectional view of the device, taken on the line 2—2, Fig. 1, looking in the direction of the arrows; Fig. 3 is a partially sectioned, elevational view of the device with an alternate form of anchoring for play; Fig. 4 is a side view of one of the ball anchoring staples, and Fig. 5 is a sectional view of an alternate form of anchorage.

In Fig. 1, there is shown the plan view of the structure shown in Fig. 2. In this latter figure the practice ball, as shown in transverse section, is made of moulded rubber, and has the ball portion 1 made in a globular form. The wall of the ball is made relatively thin, so that it readily collapses and deforms upon being struck by a

golf club, as is shown by the dotted lines A—B. To increase the rapid collapse of the ball under impact, the upper portion of the hollow ball is open or provided with a relatively large air vent 5, so that the ball at all times tends to rapidly discharge its air content and as rapidly recover its spherical form, from a blow. The action is instant and lively.

The globular portion 1, as in Fig. 2, has an integrally moulded cylindrical neck portion 2, of somewhat smaller diameter at its middle than at its ends and has a widened base portion 3, in which may be moulded a metallic threaded plug 6. The plug 6 has a plurality of ribs 8 on its outer exterior, so that when moulding the ball 1—2, the mold-in plug 6 will, thereafter, be held in operative position in the base 3. The upper portion of the neck 2 is so developed that it merges gradually, as at a—a into the ball contour with easy curves, and this permits the neck and ball structure to be extremely flexible, when mounted for play action, under the force of a driving stroke of a club.

In the views of Figs. 1 and 2, 12 represents the ground, having a suitable surface 14, and in 80 which a hole is dug. Thereafter a tapering concrete plug 11, having a stud 9 moulded therein, with a head 10 at its lower end and an extending threaded stud end 7 thereon, is buried in the hole, some of the soil is replaced and tamped to 85 firmly anchor the base or ball anchor 11 therein, and a somewhat circular depression 13, is left above the ball anchor 11, so that when the ball 1—2 is screwed to stud end 7 it projects above the ground, as in Fig. 2, at about teeing height. 90

As thus mounted the player stands on the ground, and can practice striking the ball, in a natural manner. After play, the ball may be unscrewed leaving the base 11, as a permanent buried anchorage, well positioned below the 95 ground line 14, and thus not interfere with grass cutting and the like.

In Fig. 5 there is shown an alternate form of base or ball anchorage, the same being in the form of a cast or stamped out metal cup 18, the 100 cup, like the base 11, having an outwardly tapering flare from its top to its base, and having an anchoring flange 19 at its lower open end. A ball attaching stud is firmly mounted, by its head 20, to the upper part of base 18, its thread end 21 extending upwardly, to receive the ball thereon as described for Fig. 2. This cup, like the base 11, is also intended to be permanently buried in the ground to serve as a ball anchorage, as described for Fig. 2.

In Fig. 3, there is shown another form of ground anchorage for the ball 1. In this latter anchorage the cupped ground hole 13 is made, and the base 3 of the neck 2 placed in the bottom 5 of the hole 13, and then two long wire staples 15—15, shown in full in Fig. 4, are driven diagonally into the ground, crosswise, so that their joint opposed loop ends 16 embrace the opposite sides of the neck portion 2, and thus hold the 10 play ball firmly in position for practice. The staples have sharpened ends 17 for ease in driving them into the ground.

As thus outlined, it will be noted that I have provided a play or practice ball of light, elastic 15 and lively action, which under the practice strokes of the player, is phantom like in play, and which, owing to its lightness and elasticity is not easily injured, and is, therefore resistant to wear. It is easily mounted and dismounted, and 20 is an excellent means for permitting the player to study the strokes as made and to perfect his drive.

Further, because the ball is anchored to the ground, the player stands on the ground and 25 can practice with more confidence than if standing on an elevated platform.

Having thus described my invention what I claim is:

1. A golf practice apparatus comprising in 30 combination a base having in its top surface a recess, a ball including a resilient shell and having a top provided with a breather opening of sufficient size to permit substantially unrestricted passage of the air upon collapse of the ball, a stem integral with said shell and disposed 35 therebelow, said shell being above the level of said surface, and means attaching the lower end of said stem to said base at the bottom of said recess, so that as said shell is struck one side thereof may returnably bend over the top of said stem, the opposite side of said shell being returnably bendable over said surface.

2. A golf practice apparatus comprising in 40 combination a base having in its top surface a recess, a ball including a resilient shell having a top provided with a breather opening of sufficient size to permit substantially unrestricted passage of the air upon collapse of the ball, a single stem integral with said shell and disposed 45 therebelow, said shell being above the level of said surface, fastening means rigid with said base at the bottom of said recess, and means carried by the lower end of said stem and attaching the latter to the first mentioned means, so that as 50 said shell is struck opposite sides thereof may yield practically separately.

3. An apparatus for golf practice comprising 55 in combination with a ground having a flat surface, said surface having therein a recess, a rubber ball disposed above said surface and including a shell having a top provided with a breather opening of sufficient size to permit substantially unrestricted passage of the air upon collapse of

the ball, a single stem integral with said shell and disposed below the base portion thereof, and means attaching the lower end of said stem to said ground in the bottom of said recess, so that as said shell is struck one side thereof may bend over said base portion the opposite side of said shell being bendable over said surface and the top end of said stem being bendable in said recess. 80

4. A golf practice apparatus comprising in 85 combination a base having therein a recess, a rubber ball disposed above said base, a stem integral with said ball and disposed therebelow, and means attaching the lower end of said stem to said base at the bottom surface of said recess; said means including an internally threaded bushing which is moulded into said lower end, and a fastening element rigid with said base and having an externally threaded shank projecting above said bottom surface for cooperating with the first mentioned threads, whereby said ball with its stem may be threadedly turned into attached position. 90

5. An apparatus for golf practice comprising in 95 combination a base or ground having in its top surface a recess, a vertically disposed rubber stem, means attaching the lower end of said stem to said base at the bottom of said recess, said stem having its top end at least as high as said surface, a thin shell rising from the outer periphery of said top end and integral therewith, said shell simulating a golf ball and having a top provided with a breather opening of sufficient size to permit substantially unrestricted 100 passage of the air upon collapse of the ball, so that as a golf club strikes said shell the thin wall thereof may returnably collapse, one side of said shell being bendable over said top end and the opposite side of said shell being bendable over 105 said surface. 110

6. A practice ball comprising a hollow soft rubber ball having an unobstructed interior provided at its top with a breather opening of sufficient size to permit substantially unrestricted 115 passage of air upon collapse of the ball under influence of a blow, a solid flexible rubber supporting stem integral with the ball and projecting from the ball opposite said opening, and means to secure said stem in a substantially vertical position on a base. 120

7. A practice ball comprising a hollow soft rubber ball having an unobstructed interior provided at its top with a breather opening of sufficient size to permit substantially unrestricted passage 125 of air upon collapse of the ball under influence of a blow, a solid flexible rubber supporting stem integral with the ball and projecting from the ball opposite said opening, the wall of said ball merging into said stem by a gradually thickened portion, and means to secure said stem in a substantially vertical position on a base. 130
